INVENTOR WALTER CYRUS PITTS

BY HIS ATTORNEYS Smith & Rogers

UNITED STATES PATENT OFFICE.

WALTER CYRUS PITTS, OF PHILADELPHIA, PENNSYLVANIA, ASSIGNOR TO HAWTHORNE & SHEBLE MANUFACTURING COMPANY, OF PHILADELPHIA, PENNSYLVANIA, A CORPORATION OF PENNSYLVANIA.

DESIGN FOR A CABINET.

No. 39,909.

Specification for Design.

Patented April 6, 1909.

Application filed January 21, 1909. Serial No. 473,586. Term of Patent 7 years.

To all whom it may concern:

Be it known that I, WALTER CYRUS PITTS, a citizen of the United States, residing in Philadelphia, Pennsylvania, have invented a new, original, and ornamental Design for a Cabinet, of which the following is a specification.

In the accompanying drawing forming part of this specification the figure is a per-

spective view of the cabinet showing my new design.

I claim:

The ornamental design for a cabinet, as shown.

WALTER CYRUS PITTS.
